UNITED STATES PATENT OFFICE

FRANK A. C. KRUEGER, OF MILWAUKEE, WISCONSIN

LAUNDRY BREAKING TABLE

Application filed November 22, 1930. Serial No. 497,562.

The invention relates to improvements in laundry breaking tables.

One of the objects of the present invention is the provision of an improved type of laundry breaking table, particularly adapted for sorting clothes in laundries, and includes means to increase the efficiency of sorting the fugitive colors from the white clothes, and also the articles which are to be hand-washed, and the device is so constructed that an unskilled operator may readily carry out the purpose of the device.

Another object of the present invention is the provision of a laundry breaking table including a plurality of stalls, in which is arranged a sectional receiver, and a main receiver suspended from the table or platform whereby the clothes can be deposited upon the platform and quickly sorted; with the white clothes being deposited in the main container, or what is known as the customer's laundry bag, while the remaining articles are sorted according to colors and type of articles to correspond to the cleaning process for each article, as it is necessary to sort these articles into separate units for laundrying purposes.

A further object of the present invention is the provision of a laundry breaking table constructed so as to provide a plurality of stalls, whereby several sets of laundries can be sorted at one time and one or more operators can be doing the sorting in accordance with the amount of work to be done, thus saving considerable time in the sorting and providing a device whereby an unskilled operator may carry out the work with the desired efficiency.

With the above and other objects in view, the invention consists in the novel features of construction, the combination and arrangement of parts hereinafter more fully set forth, pointed out in the claims and shown in the accompanying drawings wherein:

Figure 1 is a top plan view of a laundry breaking table, constructed in accordance with my invention;

Figure 2 is a side elevation;

Figure 3 is a detailed vertical section il-

lustrating the amount of the main laundry bag; and,

Figure 4 is a detailed vertical section illustrating means for maintaining the table in a central position.

In the construction of this device, I provide an angular floor plate 1, the horizontal portion of which is attached to the floor of the laundry by means of the lag screws 2. The vertical portion of the plate 1 has engaged therewith upon the interior, a depending flange 3, carried by the angular plate 4 on the center portion 5 of the device. Extending radially from the center portion 5 are a plurality of partition members 6, arranged in equal spaced relation as shown in Figure 1.

Arranged between the partition members 6 are the platforms 7, each provided with an opening 8 and arranged in each opening 8 is a collar 9 having an annular bead 10 at its upper end.

The main laundry bags 11 are suspended through the openings 8 by having the upper edge of the bag drawn over the bead 10 and the clamping ring 12 engaged over the bead 10 to clamp the material therebetween. The clamping ring 12 is hinged to the platform 7, as shown at 13, and is adapted to be moved to a substantially vertical position when not in use, as shown by the dotted lines in Figure 3. The clamping ring 12 is maintained in a vertical or inoperative position by means of a spring clip 14.

Mounted upon each platform 7 and arranged between the upper portions of the partitions 6 are the containers 15, divided into separate compartments, as shown at 16, the several compartments being adapted to receive the various types of laundry. It will, therefore, be apparent that when it is desired to assort a bundle of laundry, the bundle is placed upon one of the platforms 7 and opened. The articles are then sorted according to colors, and the types of washing for the different articles. In other words, the white clothes are placed within the laundry bag 11, while the remaining articles are sorted according to colors and type of material, with all of the smaller articles; such as col-

lars, handkerchiefs, and the like, being deposited in one section of member 15.

Prior to removing the articles from the laundry bag or bundle, the marker pin is removed from the outside of the package placed in a convenient position within each area formed by the partition members 6. Therefore, after the articles have been assorted, they can be readily tagged and sent to the washroom, with the different classes of articles being washed by different processes.

In using a device of this character, it will be noted that an unskilled operator can be used for sorting the materials, as it is not a difficult operation to place different types of clothes in the several compartments 16.

After the several articles have been properly classified, the tag operator then applies the proper marking pins to the articles and they are carried out to the washroom where they are put through the different operations for cleansing purposes. With the use of this type of table, several lots of articles to be laundered can be very quickly and easily separated and result in a minimum number of errors which usually occur in the sorting of laundry. The containers 15 are substantially triangular in shape with the apex arranged adjacent the tubular member 5, while the base of the container faces outwardly of the device and these containers are so mounted that they can be readily moved relative to the platforms 7 when it is desired to remove the articles therefrom. Extending around the platforms 7, at the outer ends thereof, is the guide rail, 17 which reduces to a minimum the number of articles being accidentally displaced relative to the platforms.

Attached to the lower end of each wall 6 are casters 18 which are adapted to rotatably support the device as shown in Figure 2, and the device is retained in a central position by means of the angular plates 1 and 4.

It will be apparent from this arrangement that an operator can stand in one location relative to the device and easily sort out the articles in the various laundry packages. The central upright member is securely retained against lateral movement by means of the flange plates 1 and 4.

It will thus be apparent that when the two angular plates 1 and 4 are arranged in the position shown in Figure 4, the entire device can be moved around a central point and will be securely retained against movement away from this point. Therefore, an operator can stand in one position, sort the laundry in one of the sections formed by the partition members 6, thus rotating the device on the casters 18 until the next adjacent section has been positioned in front of the operator. This operation may be carried out until all of the laundry in the several sections has been sorted.

It is believed that with a device of this

character it will save considerable time and expense in the sorting of laundry at large laundries, due to the fact that even an unskilled operator after instructions can readily assort a bundle of laundry, placing the proper articles in the proper compartments 16 and assemble all of the white clothes in the main laundry bags 11.

The device is inexpensive for the character of the work to be carried out and it is believed it will save considerable time and expense in laundries handling a large volume of business.

Between the partitions 6 adjacent the lower ends thereof, I provide the base platforms 19 which can be used for various purposes, but are preferably used for supporting the main laundry bags 11, as shown in Figure 2.

While I have shown and described the preferred embodiment of my invention, it will be apparent from the foregoing that slight changes may be made in the construction when putting the invention into practice without departing from the spirit of the same or the scope of the appended claims.

I claim:

1. A laundry breaking table comprising a central pedestal, a plurality of spaced radial partitions carried by said pedestal to form individual stalls, sorting shelves in each of said stalls, rollers carried by the outer ends of said partitions for supporting the same, an annular depending flange carried by the bottom of the pedestal, and means mounted on the floor and engaging said flange to rotatably anchor the table on the floor.

2. A laundry breaking table comprising a central pedestal, a plurality of spaced radial partitions carried by said pedestal to form individual stalls, upper and lower shelves in each of said stalls, the upper shelves being provided with bag receiving openings, bags supported on the lower shelves and projecting through said openings, means carried by said upper shelves for detachably securing the mouths of said bags thereto adjacent said openings, rollers carried by the outer ends of said partitions for supporting the same, and means for rotatably anchoring said pedestal on the floor.

3. A laundry breaking table comprising a central pedestal, a plurality of spaced radial partitions carried by said pedestal to form individual stalls, upper and lower shelves in each of said stalls, the upper shelves being provided with bag receiving openings, bags supported on the lower shelves and projecting through said openings, means carried by said upper shelves for detachably securing the mouths of said bags thereto adjacent said openings, rollers carried by the outer ends of said partitions for supporting the same, means for rotatably anchoring said pedestal on the floor, and a partitioned container sup-

ported on each of the upper shelves adjacent said pedestal and between the adjacent partitions.

4. A laundry breaking table comprising a central pedestal, a plurality of spaced partitions carried by said pedestal to form individual stalls, upper and lower shelves carried by said partitions for each stall, said upper shelves being provided with bag receiving openings adjacent one of the partitions, bags supported upon the lower shelf and projecting through said openings, a hinged retaining means mounted adjacent said openings for detachably retaining the mouths of said bags to the edges of said openings, partitioned containers supported upon the upper shelves adjacent said pedestal and said partitions, rollers carried by the outer ends of said partitions for supporting the same, a depending annular flange secured to the bottom of said pedestal, an upwardly projecting annular flange secured to the floor and engaging said depending flange to rotatably anchor the table on the floor.
- 25 In testimony that I claim the foregoing I have hereunto set my hand at Milwaukee, in the county of Milwaukee and State of Wisconsin.
